Term of patent 14 years

Int. Cl. D23—01

U.S. Cl. D23—45

FIG. 1 is a side elevational view of a corrugated pipe showing my new design, with the opposite side thereof being substantially the same as that shown;

FIG. 2 is an end view thereof taken from the left of FIG. 1;

FIG. 3 is a sectional view taken substantially along line 3—3 of FIG. 1;

FIG. 4 is a side elevational view of a second embodiment of the corrugated pipe shown in FIG. 1, the opposite side being a mirror image of the side shown;

FIG. 5 is an end view taken from the left of FIG. 4;

FIG. 6 is a sectional view taken along line 6—6 of FIG. 4;

FIG. 7 is a side elevational view of a third embodiment of the corrugated pipe shown in FIG. 1, the opposite side being a mirror image of the side shown;

FIG. 8 is an end view taken from the left of FIG. 7; and

FIG. 9 is a sectional view taken along line 9—9 of FIG. 7.

A portion of the corrugated pipe has been broken away in FIGS. 1, 4 and 7 to indicate indeterminate length.

I claim:

The ornamental design for a corrugated pipe, substantially as shown and described.
